(57) **CLAIM**

We claim the ornamental design for a bicycle carrier rack, as shown and described.

DESCRIPTION

FIG. 1 is a perspective view of a bicycle carrier rack;
FIG. 2 is a right side elevational view of a bicycle carrier rack;
FIG. 3 is a left side elevational view thereof;
FIG. 4 is a top plan view thereof;
FIG. 5 is a bottom plan view thereof;
FIG. 6 is a front elevational view thereof;
FIG. 7 is a rear elevational view thereof;
FIG. 8 is a right side elevational view of a second embodiment of a bicycle carrier rack;
FIG. 9 is a left side elevational view thereof;
FIG. 10 is a top plan view thereof;
FIG. 11 is a bottom plan view thereof;
FIG. 12 is a front elevational view thereof;
FIG. 13 is a rear elevational view thereof;
FIG. 14 is a right side elevational view of a third embodiment of a bicycle carrier rack;
FIG. 15 is a left side elevational view thereof;
FIG. 16 is a top plan view thereof;
FIG. 17 is a bottom plan view thereof;
FIG. 18 is a front elevational view thereof;
FIG. 19 is a rear elevational view thereof;
FIG. 20 is a right side elevational view of a fourth embodiment of a bicycle carrier rack;
FIG. 21 is a left side elevational view thereof;
FIG. 22 is a top plan view thereof;
FIG. 23 is a bottom plan view thereof;
FIG. 24 is a front elevational view thereof; and,
FIG. 25 is rear elevational view thereof.

Broken lines, including any boundary created thereby, are included for the purpose of illustrating environment, and do not form a part of the claimed design.
